UNITED STATES PATENT OFFICE.

HENRY PEARSON, OF BALTIMORE, MARYLAND.

REFRIGERATING-TANK FOR TRANSPORTING MILK AND OTHER DAIRY PRODUCTS.

SPECIFICATION forming part of Letters Patent No. 425,578, dated April 15, 1890.

Application filed September 6, 1889. Serial No. 323,188. (No model.)

To all whom it may concern:

Be it known that I, HENRY PEARSON, a citizen of the United States, residing at No. 25 Madison street, Baltimore, in the State of Maryland, have invented certain new and useful Improvements in Refrigerating-Tanks for Transporting Milk and other Dairy Products; and I do hereby declare the following to be a full, clear, and exact description of the invention, such as will enable others skilled in the art to which it appertains to make and use the same.

This invention relates to certain new and useful improvements in refrigerating-tanks for transporting milk and other dairy products.

Referring to the accompanying drawings, forming a part of this specification, Figure 1 is a perspective view of my improved refrigerator, a portion of the foot-board of the vehicle in which it is carried being shown; Fig. 2, a vertical longitudinal section of the refrigerator and vehicle through the compartment a' ; Fig. 3, a perspective view showing the lid of the refrigerator raised; Fig. 4, a vertical longitudinal section through the compartment a^2 ; Figs. 5 and 6, detail views of the faucet and its fastening; Fig. 7, a perspective view of a slightly-modified form of refrigerator.

Referring to the drawings, the letter A indicates the body of my refrigerator. This body is made nearly as large as the box of the vehicle which is designed to carry it, and its front end is cut away, as shown at a^* , to form a seat for the driver. A longitudinal partition a divides the refrigerator-body into two compartments a' a^2 , as seen in Fig. 3.

C indicates the milk-can, which is of a size and shape to snugly fit the compartment a' , and is provided at its forward end with an extension c^* to fit under the driver's seat, a space being left between the top of said can and the cover of the refrigerator, which is filled with ice. The neck c is raised above the top of the can to facilitate filling and to bring its mouth above the ice to guard against the accidental entrance of ice or water into the can. Said neck is closed by means of any suitable cover, and the cover has connected thereto a small tube c^2 , which projects up through a suitable aperture in the cover of

the refrigerator, its purpose being to supply a small quantity of air to the can, and thus act as a vent in drawing off the contents thereof. The bottom of the can is inclined from its rear to its front end, in order that all the milk may be drawn from the can, and is supported on inclined cleats c' , in order to raise its rear end. The front end of the can is provided with a tube c^2 , having its interior tapered for the purpose hereinafter described, and said tube, when the can is in place, projects through an aperture in the front of the refrigerator and through a corresponding aperture in the front end of the wagon-body.

Immediately over the aperture in the wagon-body is secured a raised boss D, having a central opening d and provided upon its under or inner face with two inclined or wedge-shaped flanges d' d^2 . Upon opposite sides of the central opening d and communicating therewith are slots d^2 d^2 .

E indicates a faucet having a tapered end to fit the tapered bore of the tube c^2 and provided with two lugs e e . The faucet is inserted in the tube c^2 , the lugs e e passing through the slots d^2 d^2 , and is given a partial turn, the lugs e e riding over the wedge-shaped flanges d' d^2 , thus forcing the tapered end of the faucet tightly in place in the tube c^2 . The valve-plug of the faucet is squared at its top, over which fits a key F, supported upon the front of the wagon-body by means of a staple or eye f or other similar fastening.

The can may be made sufficiently large to entirely occupy the compartment a' of the refrigerator, or two or more cans may be placed therein side by side. The compartment a^2 may be employed for the storage of cream or butter-milk, and also for the storage of cans such as are ordinarily employed in transporting milk by railway. The forward end of this compartment under the driver's seat is provided with a series of drawers, that may be employed for carrying butter or other produce or articles.

The refrigerator is closed at its top by a cover composed of the hinged lids g g' g^2 g^3 , which afford access to the two compartments a' and a^2 and at both ends of the compartments. The lids g , g' , and g^2 are hinged to a rod h , whose ends lie in bearings formed in blocks h' h^2 . One of these blocks, as h' , is

provided with a two-part bearing composed of two metallic plates h^3 h^4 , each having formed therein half of the bearing, as shown, the two plates being hinged together at one end and secured together at their other ends by means of a set or thumb screw. The cover is placed in position by inserting one end of the rod h in the bearing h^2 and dropping the other end in the lower half of the two-part bearing h' and swinging the other member of the bearing in place and fastening it by means of the thumb-screw.

To the bottom of the refrigerator are affixed rollers i i , which run on rails or cleats secured to the bottom of the wagon, and at the ends of the rails the said bottom is grooved, as at k k , so that when the refrigerator is pushed in place in the wagon the rollers i i will drop into said grooves, thus allowing the refrigerator to rest squarely on its bottom. Instead of the rollers running on rails, they may rest directly on the bottom of the wagon.

The refrigerator is designed to entirely fill the body of the wagon, and can be readily removed for cleaning and easily replaced, and while being cleaned or removed for any other purpose the wagon may be employed for carrying a similar refrigerator to that removed or for other purposes.

3c. In Fig. 7 I have illustrated a slightly-modified form of refrigerator. As shown in said figure, the refrigerator is designed to be mounted directly on running-gear, instead of being placed in a wagon, and is provided with a covered compartment L in front of the driver's seat for the storage of cans or other articles.

The refrigerator should be lined with galvanized sheet-iron or with any non-conduct-

ing material, and the bottom of the cover should have a rubber or other suitable packing to prevent the entrance of air.

What I claim is—

1. The combination, with the refrigerator-body A, provided at its front with the seat a 45 and divided longitudinally into two compartments a' a'' , of the removable can C, fitting within the compartment a' and provided at its forward end with an extension c' , fitting under the seat a , and upon top at its rear end 50 with an elevated neck c , closed by a cover provided with a vent-tube c^3 , and a faucet E, communicating with said can and removably connected with said can and refrigerator-body, all constructed and arranged substantially as shown and described.

2. The combination, with the refrigerator A, having bearings h' h^2 upon each side thereof, of the rod h , removably secured in said bearings, and the sectional cover having two or more of its hinged sections hinged to said rod, substantially as shown and described.

3. The combination, in a milk-wagon provided upon its bottom with grooves k , of the removable refrigerator-body A, having secured to its under side rollers i , adapted to rest in said grooves and provided with a removable can C, and a faucet E, communicating with said can and detachably connected 70 to the wagon-body, substantially as shown and described, and for the purpose specified.

In testimony whereof I affix my signature in presence of two witnesses.

HENRY PEARSON.

Witnesses:

J. HENRY KAISER,
A. L. EVANS.
